UNITED STATES PATENT OFFICE

MATTHEW PANCHICK, OF DETROIT, MICHIGAN

ACETYLENE-GAS GENERATOR

Application filed February 1, 1928. Serial No. 251,219.

This invention relates to acetylene gas generators and has for an object the construction of such a structure which may be transported and at the same time efficiently generate acetylene gas.

Another object of this invention is the construction of an acetylene gas generator consisting of a gas generating chamber and supported thereby a water reservoir, with efficient means for forming a gas tight connection therebetween.

Another object of this invention is the production of an acetylene gas generator embodying a water reservoir supported upon a gas generating chamber, together with means for binding the reservoir and chamber together.

Another object of this invention is the formation of an acetylene gas generator including a gas generating chamber, within which is removably supported a sheet metal tray adapted to receive sediment and permit gas to escape therefrom and a wire mesh tray fitted within the sheet metal tray adapted to carry the calcium carbide.

While the accompanying drawings and the description which is to follow, constitute a disclosure of the preferred embodiment of the invention, it will be understood that various changes may be made within the scope of what is claimed.

In the accompanying drawings:

Figure 1 is a view in elevation of the apparatus embodying the invention, the view being of a schematic nature;

Figure 2 is a vertical diametric sectional view through the generator of the apparatus;

Figure 3 is a horizontal sectional view taken substantially on the line 3—3 of Figure 2 looking in the direction indicated by the arrows;

Figure 4 is a vertical longitudinal sectional view through the carburetor of the apparatus;

Figure 5 is a vertical sectional view through one of the drying units for drying the gas prior to its delivery to the carburetor;

Figure 6 is a vertical sectional view through the supply pipe by which water is admitted to the generator;

Figure 7 is a view similar to Figure 4 illustrating a slight modification of the invention.

As illustrated in Figure 1 of the drawings, the system or apparatus embodying the invention includes a generator which is indicated in general by the numeral 1, a pair of drying units indicated one by the numeral 2 and the other by the numeral 3, a source of compressed air supply indicated by the numeral 4, and a carburetor indicated by the numeral 5.

The construction of the generator 1 is best illustrated in Figures 2, 3 and 6 of the drawings and, as shown most clearly in Figure 2, the generator comprises a water reservoir 6 and a generating chamber 7. The water reservoir 6 and generating chamber 7 are of general cylindrical form and the said reservoir is disposed upon the top of the generating chamber and is provided at the periphery of its bottom with an annular seating groove 8 which opposes a similar groove 9 formed at the periphery of the top of the generating chamber 7, the groove 9 being pro-

vided in a flange 10 which projects inwardly from the upper edge of the circumferential wall of said chamber, and the chamber being open at its top. A packing ring or gasket 11 of rubber is disposed within the matching grooves 8 and 9 and serves to prevent the escape of acetylene gas from the generating chamber 7. In order that the reservoir 6 and generating chamber 7 may be separably connected in assembled relation and securely held together so as to suitably compress the gasket 11 and prevent the escape of acety-

lene gas, a stem 12 is secured in any suitable manner at its lower end as at 13 to the upper side of the bottom of the generating chamber 7 centrally thereof and extends upwardly and through a tube 14 which is arranged centrally within the generating chamber 7 and united at its upper and lower ends, in an air-tight manner, to the top and bottom of the said chamber, a nut 15 being threaded onto the upper end of the stem 12 and binding against a washer 16 which is arranged upon the said end of the stem and bears upon the upper side of the top of the generating cham-

ber 7.

ber and closes the upper end of the said tube 14, it being understood that by loosening and removing the nut 15, the generating chamber and reservoir may be separated for the purpose of introducing a fresh supply of calcium carbide into the generating chamber.

A circumscribing flange 7' is formed upon the inner surface of the circumferential wall of the generating chamber near the top of said chamber, and this flange constitutes a support for a substantially circular tray 17 comprising a circumferential wall 18 and a bottom 19, the circumferential wall 18 of the tray being provided at its top with an outstanding flange 20 which rests upon the flange 7', the tray being in this manner removably supported within the generating chamber. For a purpose to be presently explained the circumferential wall of the tray 17 is formed with a number of perforations indicated by the numeral 21. Arranged within the tray 17 is a similarly formed tray indicated by the numeral 22 comprising a circumferential wall 23 and a bottom 24, this tray being of wire mesh material and of a diameter and depth somewhat less than the corresponding dimensions of the tray 17 so that the circumferential walls and bottoms of the two trays will be mutually spaced. The circumferential wall 23 of the tray 22 is provided at its upper edge with an outstanding flange 25 which rests upon the flange 20 of the tray 17. A tube 26 is secured at its lower end to the upper side of the bottom 19 of the tray 17 and extends upwardly within the tray and a short distance above the same so as to have its upper end presented relatively close to the under side of the bottom of the reservoir 6, and the stem 12 extends upwardly 40 through this tube.

In order that a supply of water may be initially introduced into the reservoir 6, the reservoir is provided upon its top with a filling spout 27 which is closed by an air-tight cap 28. In carrying out the invention, water is supplied from the reservoir, in regulated quantities, to a mass of calcium carbide which is arranged within the tray 22, so as to effect the generation of the acetylene gas, and 50 in order that this supply of water may be effected and controlled, means is provided which will now be described.

The means referred to above for supplying water from the reservoir 6 to the generating chamber 7 comprises a water supply tube 29 which is fitted through openings 30 and 31, in an air-tight manner, formed in the top and bottom respectively of the reservoir 6, the said tube extending upwardly above 60 the top of the reservoir and downwardly beneath the bottom thereof with its lower end terminating within the tray 22 above the bottom of said tray. In that portion of its length which extends between the top and bottom of the reservoir 6, the tube 29 is

formed with a plurality of small perforations indicated by the numeral 32, and the lower end of the tube is reduced in diameter and interiorly tapered as at 33 to provide a delivery orifice of relatively small diameter and a valve seat. At this point it will be understood that water, contained within the reservoir 6, is delivered through the perforations 32, from the reservoir, into the tube 29 and is delivered, by way of the orifice 33, at 70 the lower end of said tube, into the mass of calcium carbide which is supported within the tray 22. In order that the flow of water from the lower end of the tube 29, into the mass of calcium carbide within the tray 22, 75 may be regulated, a coupling 34 is applied to the upper end of the tube and is closed at its upper end by a cap 35 having a central threaded opening 36 in which is adjustably mounted the threaded upper portion 37 of a valve rod 38 the lower end of which is tapered as at 39 so as to conform to the valve seat which surrounds the orifice 33 within the lower end of the tube 29, a hand wheel 40 being provided at the upper end of the valve rod whereby the rod may be adjusted so as to vary the position of its tapered lower end with respect to the said valve seat. At this point it will be understood that water is supplied, substantially drop by drop, to the calcium carbide, by way of the lower end of the tube 29, and in order that the supply of water may be insured and to prevent any likelihood of clogging of the orifice 33, means is provided for supplying air under pressure 80 to the said tube 29, and for this purpose the coupling 34 is provided with a radial branch 41 to which a compressed air supply pipe 42 may be connected.

The compressed air supply pipe 42 is connected, in a manner which will presently be explained, with a compressed air tank which is indicated in general by the numeral 43 and this compressed air tank may be arranged in any suitable position within or upon the automobile in connection with which the apparatus is installed, as for example behind the dash board. Air under pressure is supplied to the tank 43 through the medium of an air pump 44 the piston rod 45 of which is designed to be operatively connected, in any appropriate manner, with some moving part of the engine of the automobile, so that, while the engine is running, air will be compressed and supplied to the said tank, and in order that excess pressure may be avoided, a safety valve 46 of any of the ordinary types is connected with the tank and opens through one wall thereof. A pressure gage 47 is likewise preferably mounted upon the tank so that the user of the apparatus may ascertain the pressure of the air within the tank.

Air under pressure is delivered from the tank 43 by way of a pipe 48 and a cut-off valve 49 is interposed in this pipe and may be 130

adjusted to full closed position, when the engine is not running; so as to trap, within the tank 43, air which is present therein, under pressure, at the time the engine is stopped. A coupling 50 is connected with the pipe 48 beyond the valve 49, and the pipe 42, which leads to the water supply tube 29, hereinbefore described, is connected to this coupling, and a manually operable cut-off valve 51 is interposed in the length of the said pipe 42 and may be adjusted so as to regulate the supply of air under pressure by way of the said pipe 42 to the water supply tube 29. A coupling 52 is connected to the lower end of the pipe 48 and a compressed air supply pipe 53 is connected at one end to this coupling and at its other end is placed in communication with the generating chamber 7 as clearly shown in Figures 1 and 2 of the drawings, a manually adjustable cut-off valve 54 being interposed in the said pipe 53 so that the air under pressure, delivered to the generating chamber 7 by way of the pipe 53 may be controlled.

As stated, the compressed air tank 43 may be located behind the dash board of the automobile, and the pump 44 is intended to be operated by some moving part of the engine or the transmission and therefore located relatively remote from the tank 43, and therefore a flexible air hose 45' is provided to establish connection between the pump and the said tank. The generator 1 may be mounted at any desired point but preferably upon one of the running boards of the automobile.

In order that the generated acetylene gas may be thoroughly dried and all impurities separated therefrom prior to delivery of the gas to the carburetor 5, the gas is caused to circulate through the drying units 2 and 3, and as illustrated in Figure 5 of the drawings, these units, which are of counterpart construction, consists each of a chamber 55 which may be of metal and within which absorbent cotton or any other suitable absorbent and filtering material 56 is arranged, each chamber having a relatively large mouth 57 through which the material 56 may be introduced and this mouth being exteriorly threaded as at 58 for the application thereto of a cap 59. A pipe 60 is connected by a short length of rubber hose 61, with a short delivery pipe 62 which extends from the generating chamber 7, and is coupled as at 63 to the upper end of a tube 64 which leads downwardly through the cap 59 and into the mass of material 56 within the chamber 55 of the drying unit 2. A shorter tube 65 is likewise mounted in the cap 59 of this chamber and is connected by a coupling 66 with one end of a pipe 67 which leads to a coil 68 which is disposed to surround the exhaust manifold E of the internal combustion engine, a pipe 69 being led from the other end of this coil and connected by a coupling 70 with a tube 71 which corresponds to the tube 64 and which leads downwardly into the tank of the drying unit 3 through the top of said unit. Preferably the units 2 and 3 will be arranged at the opposite sides of the internal combustion engine in connection with which the apparatus is installed, and attaching brackets 72 may be associated with the closure caps 59 of said units for the purpose of attachment to any suitable and convenient fixed part of the automobile, or the engine thereof. The unit 3 likewise contains within its chamber 55, a mass of absorbent material corresponding to the mass 56, the units being, as previously stated, of counterpart construction, and at this point it will be evident that the acetylene gas generated in the generator 1 will be delivered, by way of the pipe 60, to the unit 2 and will circulate through the mass of absorbent material 56 within the chamber 55 of said unit and will then pass, by way of the pipe 67, to the coil 68 where it will be heated, due to the heat radiated from the exhaust manifold E and thus further dried, the mass of absorbent material 56 within the chamber 55 of the unit 2 serving to collect the sensible moisture content of the gas, and the coil 68 constituting means whereby the gas will be heated to such temperature as to evaporate the remaining moisture content of the gas. The gas is of course delivered from the coil through the pipe 69 to the unit 3 where it circulates through the mass of absorbent material within the chamber 55 of this unit, and the closure cap of this unit supports a pipe 73 corresponding to the pipe 65 of the unit 2 to which is connected, by a coupling 74, one end of a pipe 75 which leads to the carburetor of the apparatus.

The carburetor 5 of the apparatus comprises a mixing chamber which is indicated by the numeral 76 and which is preferably of the general spherical form shown in Figure 4 of the drawings, and at one side this chamber is provided with an intake spout 77 which is preferably of the flared form shown in the said figure, and a valve seat 78 is formed within the inner end of the said spout substantially at the juncture of the spout with the said chamber 76. A valve is arranged within the spout 77 of the carburetor and comprises a head 79 which coacts with the valve seat 78, and a stem 80 which extends from the head and through a guide 81 provided within the said spout, the stem slidably fitting through said guide and being provided at its outer end with a collar 82 against which bears one end of a spring 83 which is arranged upon the valve stem and which spring bears at its other end against the guide 81 thus yieldably holding the valve 79 in closed position resting upon the seat 78. At its side opposite the side from which

the spout 77 extends, the mixing chamber 76 of the carburetor 5 is provided with a tubular extension 84 which is provided at its outer end with a flange 85 adapting the same to be bolted to the intake of the intake manifold, indicated by the reference letter I, of the internal combustion engine, it being understood that the carburetor 5 of the apparatus of the present invention is to supplant the carburetor ordinarily employed and connected with the said intake manifold. The tubular extension 84 of the mixing chamber of the carburetor 5 is provided upon its upper side with an integral extension 86 having a branch 87 into which is fitted one end of the pipe 75, the dried generated acetylene gas being in this manner supplied to the carburetor by way of a passageway 88 which is formed in the extension 86 and its branch 87. In order that the supply of acetylene gas to the mixing chamber 76 of the carburetor may be controlled, a valve 89 is mounted in the said extension 86 and is provided with a port 90 which may be brought into and out of registration with the passageway 88 by rotation of the valve, the valve stem being provided in its upper end with a crank arm 91 to which is connected a rod 92 which may lead to the instrument board of the automobile upon which the apparatus is installed.

In order that a suitable volume of air may be admitted to the mixing chamber 76 of the carburetor 5, while the engine is idling, the mixing chamber is formed in its under side with an opening 92', and a valve plate 93 is slidably mounted, by a screw 94, upon the under side of the said mixing chamber and is provided with a projecting finger piece 95 which may be grasped for the purpose of adjusting the same, the valve plate having an opening 96 therein and having its portion in which the opening is formed slidably engaged in a boss 97 formed upon the under side of the mixing chamber and provided with an inlet opening 98, it being understood that by loosening the screw 94, the valve plate may be adjusted so as to vary the size of the passageway afforded by the openings 92', 96 and 98, and thus regulate the supply of air to the mixing chamber of the carburetor, the screw 94 being of course adapted to be tightened after the desired adjustment has been effected, so as to hold the said valve plate in its position of adjustment.

Figure 7 of the drawings illustrates a slightly modified form of the carburetor, and in this figure the carburetor mixing chamber is indicated by the numeral 99 and the intake nozzle by the numeral 100, the nozzle being provided in its inner end with a valve stem guide 101 corresponding to the guide 81, of the previously described embodiment, and a similar guide 102 being arranged within the inner end of the mixing chamber 99 adjacent the point of juncture of the tubular extension

103 therewith, this extension corresponding to the extension 84 of the previously described embodiment. In this embodiment of the invention the valve seat is indicated by the numeral 104 and the valve by the numeral 105, and, as illustrated in the said Figure 7, the said valve preferably comprises a valve body 106 which is of leather, and metallic disks 107 which are disposed against the opposite faces of the body 106 and secured in place by nuts 108 threaded upon the stem of the valve which is indicated by the numeral 109, the stem being slidably fitted through the guides 101 and 102, and a spring 110 being arranged upon the stem and bearing at one end against the guide 102 and at its other end against the valve head 105. In other respects the carburetor shown in Figure 7 is identical with the carburetor shown in Figure 4 and previously described.

From the foregoing description of the invention it will be understood that the valve 51 is adjusted so as to provide for the supply of air under pressure through the pipe 42 in sufficient volume to insure of the proper delivery of water from the reservoir 6 into the mass of calcium carbide within the tray 22, the valve rod 38 being adjusted so as to regulate the supply of water, and it will likewise be evident that the valve 54 may be adjusted so as to provide for the supply of air under pressure to the generating chamber 7 to cause flow of the generated gas from this chamber through the pipe 60, to the drying unit 2, where the gas is freed of the major portion of its moisture content, the gas being delivered from this unit by way of the pipe 67 to the coil 68 where the gas is heated and further dried and then delivered by way of the pipe 69 to the drying unit 3, from which it passes to the carburetor 5 and its admission to the carburetor being controlled by the throttle valve 89 which is adjusted through the medium of the rod 92. The gas which is delivered into the carburetor will of course enter the mixing chamber 76 of the carburetor where it will be mixed with air taken in through the spout 77, upon the intake strokes of the pistons of the engine, the explosive mixture thus produced being delivered to the intake manifold I and, by way of this manifold, to the engine cylinders. It will also be evident, from the foregoing, that due to the provision of the rubber hose connection 61 between the generating chamber 7 of the generator 1 and the pipe 60, if there should be an excess of gas pressure, this hose will expand and burst thus avoiding any damage to the other parts of the apparatus, it being a simple matter to replace the hose, in the event this mishap occurs.

It will be understood, in connection with the generator 1, that, due to the spacing of the peripheral and bottom walls of the tray 22 from the corresponding walls of the tray

17, a free circulation of the water through
the mass of calcium carbide is provided, and
the waste product, which is in the form of
a powder, due to the disintegration of the cal-
5 cium carbide lumps, in the generation of the
gas therefrom, may fall through the mesh of
the tray onto the bottom of the tray 17 from
which it may be removed from time to time,
as required.

10 Having thus described the invention, what
I claim is:

In a generator of the character described,
a generating chamber, an annular flange
formed upon the inner surface of the wall of
15 the chamber near the top thereof, a sheet
metal tray comprising a solid bottom having
an upstanding annular wall provided at its
top edge with a flange, the flange of the tray
engaging the flange of the chamber, the wall
20 of the tray being of less height than the wall
of the chamber, whereby said tray will be held
spaced from said chamber, a second tray of
wire mesh formed similarly to but smaller
25 than said first-mentioned tray, the flange
of the second-mentioned tray resting upon
the flange of the first-mentioned tray, where-
by the second-mentioned tray will fit within
but be spaced from the first-mentioned tray,
30 a water reservoir resting upon said cham-
ber, and means for feeding water from the
reservoir to the chamber, as and for the pur-
poses set forth.

In testimony whereof I affix my signature.
MATTHEW PANCHICK.
